UNITED STATES PATENT OFFICE.

MAX LINDEMANN, OF EAST ST. LOUIS, ILLINOIS, ASSIGNOR OF ONE-HALF TO EUGENE J. FEINER, OF ST. LOUIS, MISSOURI.

CORN-DEGERMINATOR.

1,219,117.

Specification of Letters Patent. Patented Mar. 13, 1917.

Application filed May 17, 1915. Serial No. 28,604.

To all whom it may concern:

Be it known that I, MAX LINDEMANN, a citizen of the United States, and resident of East St. Louis, Illinois, have invented certain new and useful Improvements in Corn-Degerminators, of which the following is a specification containing a full, clear, and exact description, reference being had to the accompanying drawings, forming a part 10 hereof.

My invention relates to improvements in corn degerninators, and the object of my invention is to construct a machine of this kind having two crushing elements, one arranged within the other and independently revoluble, the one only having provision for connecting with power while the other receives its motion from the first, when grain is fed between them, and is provided with a 15 braking means for governing its speed, whereby both crushing elements may be rotated at variable speeds and the crushing accomplished without choking or overheating.

With the above purposes in view, my invention consists in certain novel features of the construction and arrangement of parts hereinafter fully set forth, pointed out in my claim and illustrated by the accompanying drawings, in which—

30 Figure 1 is a longitudinal sectional elevation of a machine embodying my invention;

Fig. 2 is a transverse sectional elevation of the machine taken through the feed hopper; and

35 Fig. 3 is a view on an enlarged scale of the terminals of a band brake, showing the means for relatively hinging the band pieces and connecting them with the machine frame, and also the means for adjusting the 40 free ends of the band.

Referring by numerals to the accompanying drawings:

5 designates the frame of the machine, which is provided with the journal bearings 6 in which bearings there is mounted a shaft 7.

50 On this shaft 7 there is a pulley 8 for connection with power for the driving of the shaft and keyed to the shaft there is a hollow conical body 9 whose exterior face constitutes one of the crushing surfaces of the machine.

Formed integrally with the conical body 9 at its reduced end there is a cylindrical ex-

10 tension 10 which constitutes a feed for the 55 crushing surface of the conical body.

The end of the cylindrical extension is closed by a disk 11 and this disk projects beyond the cylindrical extension and is surrounded by a hopper 12, spaced from the 60 cylindrical extension, and supported by the frame 5 through the medium of the braces 13.

The numeral 14 designates a shell, preferably formed of mating halves, each half bearing perforated ears for connection by 65 bolts or the like, and which shell conforms substantially with the conical body 9.

The reduced end of the shell is rotatably mounted in the hopper 12, while its other end is supported rotatably upon the shaft 7. 70

At the larger open end of this shell there is a cylindrical extension 15, and surrounding this portion of the shell there is a band brake consisting of two metallic straps 16 and 17. At one end of each strap there is a 75 bearing 18, and extended through these bearings there is a bolt 19 upon which the straps may hinge. This bolt is mounted on a bracket 20, which is fixedly secured to the machine frame 5. At the other end of each 80 strap of the brake there is a flange 21, each of which is perforated to receive therethrough a threaded bolt 22. This bolt is extended through a bracket 23 fixedly secured to the machine frame opposite the bracket 85 20 and secured to the bolt is a hand wheel 24, whereby to relatively move the free ends of the straps for the purpose of varying their frictional bearing upon the cylindrical extension 15 of the shell, in order to govern 90 or control the speed of rotation of the shell. It is apparent from this showing that the machine of this application comprises two crushing surfaces whose speed of rotation may be relatively controlled, the one controlled directly by its connection with power 95 and the other receiving its motion from the first or driven element, and its speed controlled by a brake.

Having thus described my invention, what I claim as new therein and desire to secure by Letters Patent of the United States is:

In a machine of the class described, a frame, a shaft rotatably mounted on said frame, means for connecting said shaft with power, a crushing element supported by said shaft, means for causing said crushing element to rotate with said shaft, a second 105

crushing element surrounding the first mentioned crushing element and loosely mounted upon said shaft and arranged to be rotated by reason of the material acted upon between its inner surface and the outer surface of the first mentioned crushing element, a friction brake secured to the frame of the machine, and arranged to bear upon the second mentioned crushing element and means 10 for adjusting said friction brake for vari-

able pressure upon the second mentioned crushing element.

In testimony whereof, I have signed my name to this specification, in presence of two subscribing witnesses.

MAX LINDEMANN.
